DESIGN.

W. C. ESTES.
WOODEN BOX.

No. 26,819.

Patented Mar. 30, 1897.

UNITED STATES PATENT OFFICE.

WEBSTER C. ESTES, OF BROOKLYN, NEW YORK.

DESIGN FOR A WOODEN BOX.

SPECIFICATION forming part of Design No. 26,819, dated March 30, 1897.

Application filed February 19, 1897. Serial No. 624,248. Term of patent 14 years.

To all whom it may concern:

- Be it known that I, WEBSTER C. ESTES, a citizen of the United States, residing at Brooklyn, in the county of Kings and State of New York, have invented and produced a new and original Design for a Wooden Box, of which the following is a specification, reference being had to the accompanying drawings, in which—
- 10 Figure 1 is a vertical section; Fig. 2, an elevation with the cover raised, and Fig. 3 a plan.
- The general configuration of the box is round, and the leading features of my design consist in the body, having tapering or truncated conical sides with equal semicircular surface beads and with top and bottom ribs.
- 15 The design of the hollow body A comprises

the tapering or truncated conical sides *a*, having equal semicircular surface beads *b*, the top rib *c*, the bottom rib *d*, and the flat bottom *e*. 20

The design of the cover B comprises the tapering sides *f*, the approximately flat top *h*, and the raised central knob *i*.

What I claim is—

25 The design for a wooden box, substantially as shown and described.

Signed by me this 18th day of February, A. D. 1897.

WEBSTER C. ESTES.
